UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

REELING MECHANISM.

Application filed March 28, 1918. Serial No. 225,341.

To all whom it may concern:

Be it known that I, MORRIS P. HOLMES, a citizen of the United States, residing at Claremont, in the county of Sullivan and State of New Hampshire, have invented certain new and useful Improvements in Reeling Mechanism, of which the following is a full, clear, and exact specification.

My invention relates to reeling mechanism.

It has for its object to provide an improved reeling mechanism which, while not limited thereto, is especially adapted to use in connection with electrically propelled machines, and particularly to those used in mines. A further object of my invention is to provide an improved reeling mechanism especially adapted to use in connection with mining machines and comprising an improved reel truck adapted to be connected to the mining machine in such a manner as to be moved about the mine therewith, and equipped with an electric cable reel adapted to supply the current to the mining machine motor as the latter is moved from place to place. More specifically, my invention has for its object to provide an improved reeling mechanism wherein the reel is mounted and actuated in an improved manner, and whereby the movement of the same is controlled through improved cooperating mechanism. These and other objects and advantages of my improved construction will, however, hereinafter more fully appear.

In the accompanying drawings, I have shown for purposes of illustration one embodiment which my invention may assume in practice.

In these drawings,—

Fig. 1 is a plan view of my improvement applied to use in connection with a mining machine.

Fig. 2 is a transverse sectional view through the reeling mechanism, taken substantially on line 2—2 of Fig. 4.

Fig. 3 is an enlarged sectional view of the reel driving and controlling mechanism shown at the left hand side of Fig. 2.

Fig. 4 is a sectional view taken substantially on line 4—4 of Fig. 3.

Fig. 5 is a detail sectional view taken substantially on line 5—5 of Figs. 2 and 3.

Fig. 6 is a detail sectional view taken substantially on line 6—6 of Fig. 3.

In this illustrative construction, it will

be observed that I have disclosed a motor driven mining machine 1 mounted on a usual truck 2 which is adapted to be transported from place to place on the mine track 3 and supplied with power through a short lead connection 4 which in turn has its conductors electrically connected in a well known manner, as shown at 5, to a conductor cable 6 wound on a reel 7 which is in turn carried on a supplemental or trailer reel carrying truck 8 mounted on wheels 9 and herein shown to be connected to the truck 2 by means of a pivoted draw bar 10.

In my improvement, it will be observed that, as shown in Figs. 1 and 2, I have mounted the reel 7 coaxially with the wheels 9 upon the front axle 11 of the reel carrying truck 8, the reel being shown herein as fixed to a sleeve 12, which sleeve in turn encloses the axle and is suitably journaled on the frame of the truck 8. It will also be observed that the power for rotating the reel is derived from the truck wheels. More specifically, it will be noted that, in the form of the invention shown in Fig. 2, the left hand wheel 9 is provided with a coaxially disposed cap 13 suitably attached to the outer side of the wheel by means of bolts 14 and rotatably mounted on the end of the axle 11 and held in place thereon by a suitable washer and cotter connection 15. This cap 13 in turn houses within the same a ratchet wheel 16 which is splined, as indicated at 17, to the axle or shaft 11 and is engaged by a pawl 18 equipped with a well known form of spring 19 and pivotally mounted on a bolt 20 carried by and rotatable with the wheel about the ratchet, the bolt also being shown herein as serving as an additional means for clamping the cap 13 to the wheel 9. A similar mechanism to that just described is, it will be noted, also provided at the opposite end of the shaft 11, for a purpose hereinafter described.

As shown, the right hand wheel 9 is provided with an inner annular bearing flange 21 engageable with a cooperating bearing 22 formed on a sleeve 23 which is in turn fixed to the axle 11 within the wheel, and preferably formed integral with the ratchet wheel 16 and so disposed that it abuts against one end of the reel sleeve 12. The left hand wheel 9 is, moreover, provided with a similar flange 24 cooperating with a bearing member 25 herein formed integral

with the ratchet wheel 16. It will be noted, however, that the left hand bearing member 25 is also provided with internal teeth forming an internal gear 26, which is in turn 5 geared, through a pinion 27 rotatably mounted on a stud 28, to a sun gear 29 coaxially disposed with respect to the axle 11 and reel sleeve 12 at a point within the internal gear 26 and fixed to one end of the 10 reel sleeve 12 in such a manner that the two elements rotate together. Attention is also directed to the fact that the stud 28, which acts as an axis for the intermediate pinion 27, is itself carried by a rotatable 15 frame 30 preferably disposed between the internal gear and a part of the frame 8, the same preferably being journaled upon one of the bearing members 31 which act as journals for the sleeve 12. Attention is also 20 directed to the fact that the rotation of this frame 30, and, therefore, the rotation of the axis of the pinion 27, is controlled by means of a brake band 32 operatively connected at 33 to the frame in a well known manner 25 and having its braking effect controllable through rods 34 connected to an operating lever 35.

In the operation of my improved construction, it will be observed that when the 30 mining machine 1 is moved forward on the track 3, i. e., toward the left from the position shown in Fig. 1, the pawls 18 will rotate freely with the wheels 9 relative to the ratchet wheels 16 in such a manner as 35 to enable the reel to be entirely disconnected from the drive and thus permit the cable to be drawn off freely in the desired manner as the machine moves forward. When, however, the direction of movement of the machine 1 is reversed and the same is backed along the track, it will be observed that the 40 pawls 18 will then become operative, transmitting the rotation of the wheels 9 to the ratchet wheels 16, the axle 11, and the internal gear 26. As a result, it will be observed that when the brake band 32 is applied and the stud 28 is thus held stationary, 45 the pinion 27 will be rotated and in turn transmit rotation to the sun gear 29 at such 50 speed as automatically to compensate for the difference in diameter between the wheel 9 and the reel, the cable thus being taken up as desired as the machine is moved backward. Obviously, if desired to wind the 55 reel by hand at any time, rotation of the same may be permitted by manipulation of the brake band 32, the latter when it is released acting to permit the stud 28 and pinion 27 to rotate with the internal gear 26 60 about the sun gear 29 as an axis.

As a result of my improved construction, it will be noted that it is possible to control the reel in the desired manner, the same being free to unwind as the machine moves forward, and at the same time being auto-

matically operative to wind up the cable when the machine is backing, and likewise automatically disconnected when the forward movement of the machine is resumed. It will also be observed that, due to the use 70 of the ratchet mechanism on each end of the axle, the reel driving device is rendered constantly operative during backing, even under the uneven track conditions encountered in mines or when the machine is traversing curves, as one wheel is sure to be in contact with the track. Attention is also directed to the fact that through the provision of my improved construction where-in the reel is disposed coaxially with the 75 axle and wheels, it is possible to produce an exceedingly simple and compact construction well adapted to use in low entries. It will also be noted that while this improved construction may, if desired, be adapted to 80 use in other relations, it is especially adapted to service in connection with a truck of the type shown, the improved arrangement through its compactness enabling a relatively large space on the truck to be available for other purposes. These and other 85 advantages of my improved construction will, however, be clearly apparent to those skilled in the art.

While I have in this application specifically described one embodiment which my invention may assume in practice, it will be understood that the invention is not limited thereto but may be modified and embodied in various other forms without departing from its spirit or the scope of the appended claims.

What I claim as new and desire to secure by Letters Patent is:

1. In a reeling mechanism adapted for use upon a traveling member which is adapted in operation to travel alternately in opposite directions, a reel and means whereby said reel may automatically unwind upon one movement of said member and wind upon the other comprising a shaft, a member rotatable in opposite directions as said first mentioned member moves in opposite directions, a unidirectional positive driving connection between the said rotatable member and said shaft, and cooperating driving mechanism between said shaft and said reel.

2. In a reeling mechanism adapted for use upon a traveling member which is adapted in operation to travel alternately in opposite directions, a reel and means whereby said reel may automatically unwind upon one movement of said member and wind upon the other comprising a shaft, a member rotatable in opposite directions as said first mentioned member moves in opposite directions, a unidirectional positive driving connection between said rotatable member and said shaft, and planetary driving mechanism between said shaft and said reel.

3. In a reeling mechanism, a shaft, a driving member rotatable thereon, mechanism cooperating with said rotatable member for rotating said shaft in one direction, a reel 5 rotatable on said shaft, and driving connections between the reel and shaft.
4. In a reeling mechanism, a shaft, a driving member rotatable thereon, mechanism co-operating with said driving member for 10 rotating said shaft in one direction, a reel rotatable on said shaft, and planetary driving connections between said reel and shaft.
5. In a reeling mechanism, a shaft, a driving member rotatable thereon, mechanism 15 cooperating with said driving member for rotating said shaft in one direction, a reel rotatable on said shaft, and speed increasing driving connections between said reel and 20 shaft.
6. In a reeling mechanism, a shaft, a driving member rotatable thereon, mechanism cooperating with said driving member for 25 rotating said shaft in one direction, a reel rotatable on said shaft, and manually controllable driving connections between said reel and shaft.
7. In a reeling mechanism, a shaft, a driving member rotatable thereon, mechanism 30 cooperating with said driving member for rotating said shaft in one direction, a reel rotatable on said shaft, and gearing between said shaft and reel including gears rotatable with the shaft and reel and a cooperating 35 pinion.
8. In a reeling mechanism, a shaft, a driving member rotatable thereon, a ratchet wheel on said shaft, a cooperating pawl 40 rotatable with said rotatable member, a reel on said shaft, and speed varying transmission means operatively connected between said shaft and said reel for driving said reel at a different speed from that of the shaft.
9. In a reeling mechanism, a shaft, a driving member rotatable thereon, a ratchet wheel on said shaft, a cooperating pawl 45 rotatable with said rotatable member, a reel on said shaft, and speed varying transmission means operatively connected between said ratchet wheel and said reel for driving said reel at a different speed from that of the shaft.
10. In a reeling mechanism, a shaft, a driving member rotatable thereon, mechanism 55 for rotating said shaft in one direction, a reel rotatable on said shaft, and mechanism connecting said shaft and reel including an internal gear rotatable with said shaft, a gear rotatable with said reel, and a 60 cooperating pinion meshing with each of said gears.
11. In a reeling mechanism, a shaft, a driving member rotatable thereon, mechanism for rotating said shaft in one direction, 65 a reel rotatable on said shaft, and mecha-
- nism connecting said shaft and reel including gears rotatable with each of the same and a cooperating pinion and mechanism for controlling said pinion.
12. In a reeling mechanism, a shaft, a 70 driving member rotatable thereon, mechanism for rotating said shaft in one direction, a reel rotatable on said shaft, and mechanism connecting said shaft and reel including 75 gears rotatable with each of the same and a cooperating pinion and braking mechanism for controlling said pinion.
13. In combination, a shaft, a plurality of rotating members thereon, a reel disposed between the same and coaxially therewith 80 and with said shaft, means for rotating said shaft when either of said rotating members is rotated in one direction but not when the latter are rotated in an opposite direction, and cooperating means connected with 85 one of said last mentioned means for transmitting the rotation of said shaft to said reel.
14. In combination, a shaft, a plurality of rotating members thereon, a reel disposed 90 between the same and coaxially therewith and with said shaft, means for rotating said shaft when either of said rotating members is rotated in one direction but not when the latter are rotated in an opposite direction, and cooperating speed increasing means 95 connected with one of said last mentioned means for transmitting the rotation of said shaft to said reel.
15. In combination, a shaft, a plurality 100 of rotating members thereon, a reel disposed between the same and coaxially therewith and with said shaft, means for rotating said shaft when either of said rotating members is rotated in one direction but not when the latter are rotated in an opposite direction, 105 cooperating speed increasing means connected with one of said last mentioned means for transmitting the rotation of said shaft to said reel, and means for controlling 110 the connection of said last mentioned means.
16. In combination, a frame, an axle thereon a plurality of wheels on said axle, a reel journaled on said axle between said wheels, means operatively connected between 115 one of said wheels and said reel for driving the latter at an angular speed of rotation greater than that of the wheel when said wheel is rotated in one direction and automatically disconnecting said reel when said wheel is rotated in the opposite direction, and manually controlled means for interrupting the drive of said reel at will.
17. The combination with a reel, of means 120 for positively driving the reel in one direction or for automatically permitting a free rotation of the reel in the opposite direction, and comprising a driving member, and a ratchet driving mechanism between said driving member and said reel.

18. The combination with a reel, of means for positively driving the reel in one direction and for permitting a free rotation of the reel in the opposite direction, and comprising a ratchet driving mechanism, and a planetary driving mechanism between said driving mechanism and said reel.
19. In combination with a portable reel and carrying means therefor, a shaft, a rotatable driving member having a peripheral speed equal to the speed of translation of the reel, driving mechanism between the shaft and rotatable member, and cooperating driving mechanism between said driving mechanism and the reel.
20. A portable reeling mechanism comprising a truck, a shaft thereon, a rotatable driving member having a peripheral speed equal to the rate of movement of the truck, driving mechanism between the shaft and the rotatable member, a reel, and planetary driving mechanism between said driving mechanism and said reel.
21. In a reeling mechanism, a shaft, a rotatable driving member concentric therewith, mechanism for driving said shaft in one direction but not in the other therefrom, a reel rotatably mounted on said shaft, and driving connections between said reel and shaft.
22. A portable reeling mechanism comprising, in combination, a reel carrier, a shaft thereon, a driving member rotatable on said shaft, mechanism for rotating said shaft in one direction but not in the other, a reel rotatable on said shaft, and driving connections between said reel and shaft.
23. In a reeling mechanism adapted for use upon a traveling member of a type which in operation alternately moves away from and towards a given point, a reel, bearings therefor, a member rotatable in opposite directions as said traveling member moves on its opposite courses, a shaft, a unidirectional driving connection between said shaft and said rotatable member, and manually controlled driving mechanism between said shaft and reel.
24. In a reeling mechanism adapted for use upon a traveling member of a type which in operation alternately moves away from and towards a given point, a reel, bearings therefor, a member rotatable in opposite directions as said traveling member moves on its opposite courses, a shaft, a unidirectional driving connection between said shaft and said rotatable member, and driving connections between said shaft and reel comprising a transmission member and means for controlling the same.
25. In a reeling mechanism adapted for use upon a traveling member of a type which in operation alternately moves away from and towards a given point, a reel, bearings therefor, a member rotatable in opposite directions as said traveling member moves on its opposite courses, a shaft, a unidirectional driving connection between said shaft and said rotatable member, and driving connections between said shaft and reel comprising a transmission member and means for controlling the same.
26. In a reeling mechanism adapted for use upon a traveling member of a type which in operation alternately moves away from and towards a given point, a reel, bearings therefor, a member rotatable in opposite directions as said traveling member moves on its opposite courses, a shaft, a unidirectional driving connection between the shaft and rotatable member, and driving connections between said shaft and reel comprising a transmission member normally rotatable about a fixed pivot and means for releasing said pivot at will.
27. In a reeling mechanism adapted for use upon a traveling member of a type which in operation alternately moves away from and towards a given point, a reel, bearings therefor, a member rotatable in opposite directions as said traveling member moves on its opposite courses, a shaft, a unidirectional driving connection between the shaft and rotatable member, and driving connections between said shaft and reel comprising a transmission member normally rotatable about a fixed pivot, said pivot being mounted for bodily rotation in a fixed orbit when released, and means for releasing said pivot at will.
28. In combination, a wheeled truck having wheels at opposite sides thereof, a shaft rotatable on said truck, unidirectional driving connections between a wheel on each side of said truck and said shaft, a reel journaled on said truck, and driving connections between said shaft and reel.
29. In combination, a wheeled member adapted to run upon a track and comprising a shaft having wheels at each end thereof, a reel mounted on said member, unidirectional driving connections between each of said wheels and said shaft, and driving connections between said shaft and said reel whereby said reel may be continuously driven either on curved or straight track upon movement in one direction of said member.
30. In combination, a reel supporting truck having running gear including supporting wheels, a reel on said truck, and means for positively driving the reel in one direction and automatically permitting a free rotation of the reel in the opposite direction comprising driving connections including a ratchet mechanism between one of said truck wheels and said reel.
31. In combination, a reel, a wheeled support upon which a reel is adapted to be transported, and means for positively driving the

reel in one direction and automatically permitting a free rotation of the reel in the opposite direction as said support moves respectively towards and from a fixed point comprising driving connections between the reel and a wheel including a ratchet mechanism.

32. In combination, a reel, and reel supporting and driving means operative to travel and carry said reel alternately in opposite directions, and comprising a reel mounting,

an element rotatable as said support moves in opposite directions, and means for positively driving the reel in one direction and automatically permitting a free rotation of the reel in the opposite direction as said supporting and driving means travels in one direction or the other comprising driving connections between the reel and said element including a ratchet mechanism.

In testimony whereof I affix my signature.

MORRIS P. HOLMES.
